(57) **CLAIM**

The ornamental design for display screen or portion thereof with animated icon as shown and described.

DESCRIPTION

FIG. 1 is a front view of the first image in a sequence for a display screen or portion thereof with animated icon;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The appearance of the transitional image sequentially transitions between the images shown in FIGS. 1-6. The process or period in with one image transitions to another image forms no part of the claimed design.

The outermost broken line presents a display screen or portion thereof and forms no part of the claimed design.
